UNITED STATES PATENT OFFICE.

RUDOLPH F. BARTEL, OF BAYONNE, NEW JERSEY.

DESIGN FOR A CAP.

SPECIFICATION forming part of Design No. 25,491, dated May 12, 1896.

Application filed March 26, 1896. Serial No. 585,013. Term of patent 7 years.

To all whom it may concern:

Be it known that I, RUDOLPH F. BARTEL, a citizen of the United States, residing at Bayonne, in the county of Hudson and State of New Jersey, have invented and produced a new and original Design for Caps, of which the following is a specification.

This design has for its object to provide a novel, ornamental, and characteristic cap.

- 10 The design consists in a cap having the side gradually increasing in height from the back to the front and having the upper edge of the side projecting forward and laterally at the front and sides of the cap.
- 15 The design is illustrated by the accompanying drawings, in which—

Figure 1 shows a side elevation of the cap. Fig. 2 is a front elevation of Fig. 1.

The side 1 of the cap has its upper edge indicated at 2 3 4 and its lower edge indicated at 5 6 7. The height of the cap side gradually increases from the back to the front, as

seen by comparing the height 2 5 with the height 3 6 or 4 7.

At the front of the cap the upper edge part 4 projects forward of the lower edge part 7, and at the sides of the cap the upper edge parts 3 project laterally beyond the lower edge parts 6.

The design provides an ornamental and handsome cap which presents to the eye a distinguishing and characteristic appearance.

What I claim as new, and desire to secure by Letters Patent, is—

The design for a cap substantially as shown and described.

In testimony whereof I have hereunto set my hand in the presence of two subscribing witnesses.

RUDOLPH F. BARTEL.
